Filed Apr. 2, 1973, Ser. No. 346,949

Term of patent 14 years

Int. Cl. D23—01

U.S. Cl. D23—18

FIG. 1 is an elevational view taken from one side of a sprayer unit showing my new design;

FIG. 2 is an elevational view taken from one end thereof;

FIG. 3 is an elevational view showing the end opposite that shown in FIG. 2;

FIG. 4 is a top plan view thereof; and

FIG. 5 is an elevational view taken from the side opposite that shown in FIG. 1.

The spray hose between the nozzle and the pump has been broken away to indicate indeterminate length.

I claim:

The ornamental design for a sprayer unit, as shown and described.
